UNITED STATES PATENT OFFICE

LESTER GUY QUERRY, OF HUNTINGDON, PENNSYLVANIA

STEERABLE TAIL SKID FOR AEROPLANES

Application filed March 15, 1929. Serial No. 347,358.

The present invention relates broadly to improvements in aeronautics and more particularly to a novel tail skid for aeroplanes. The specific aim of this invention is to provide an improved tail skid, connected in such a manner with the usual rudder mechanism of the aeroplane whereby the tail skid will turn with the motion of the rudder to assist in steering the aeroplane when taxiing upon the ground.

The principal object of this invention is to provide a steerable tail skid for aeroplanes which, in use, will not tend to complicate aeroplane construction, nor be susceptible of ready development of defects.

Another object of importance is to provide an aeroplane construction including novel steering means and a novel construction of the fuselage, whereby the novel steering mechanism may be readily inspected.

These and other objects of the invention will become more apparent to the reader after considering the invention as described and claimed hereinafter.

25 In the drawings:

Figure 1 represents a fragmentary side elevation of an aeroplane constructed in the novel manner consistent with the present invention.

30 Figure 2 is a rear elevation of the improved aeroplane construction with the tail portion thereof removed.

Figure 3 is a plan view of the arm for rocking the rudder shaft.

35 Figure 4 is a collar for association with the rudder shaft and steering lever.

Figure 5 is a side elevation of a detail of the novel skid.

Referring to the drawings, wherein like numerals designate like parts, in Figure 1, numeral 3 designates the rear portion of a conventional aeroplane fuselage. In carrying out the present invention, the tail end portion of the fuselage is severed transversely at the point 4, to permit access to the adjacently located vertical shaft 5, for controlling the aeroplane rudder. The rudder shaft 5 has a rocker arm 6 secured thereto by collars 7-7. The cables 8 connect the ends of the lever 6 to suitable control means

located within the cockpit of the fuselage.

The lowermost collar 7 is adapted for rest upon the bearing body 9, which is supported upon the lower portion of the fuselage 3, in substantially the manner shown in Figure 55 2. The bearing 9 has the sleeve 10 disposed therethrough and the sleeve 10, in turn, receives the lower portion of the rudder shaft 5 and is suitably secured thereto.

The sleeve 10 has a curved depending end 60 11 secured to its lower end, and the lower end of the curved member 11 is pivotally connected as at 12 to a leg 13. A shock absorbing device 14 is interposed between the lower portion of the leg 13, and the upper 65 portion of the curved arm 11 in substantially the manner shown in Figure 1. A stream line and substantially conical shaped tail section 15 is hingedly connected as at 16, to the lower portion of the rear end of 70 the fuselage 3, suitable means, (not shown in the drawings) being provided for securing the upper portion of the section 15 to the fuselage 3. Obviously, numerous changes in the specific shape, size and materials may be resorted to, in the construction 75 of this novel aeroplane construction without departing from the spirit and scope of the invention as claimed hereinafter.

Having described the invention, what is 80 claimed as new is:

1. An aeroplane tail skid, comprising in combination, a rudder shaft, and a tail skid secured to the lower end thereof and adapted to turn therewith, said skid consisting of a 85 curved member, said curved member being connected at one end to the rudder shaft, a leg pivotally connected at one end to one end of the member, and a shock absorbing device interposed between the leg and the 90 said curved member.

2. An aeroplane tail skid, comprising a vertical shaft arranged within the tail portion of the usual aeroplane fuselage, means for rotating said shaft, a curved member secured at one end to the lower end of the shaft, a pivotal leg on said member, and shock absorbing means associated with said pivotal leg.

3. An aeroplane tail skid comprising a vertical shaft arranged within the tail por- 100

tion of the usual aeroplane fuselage, means for rotating said shaft, a curved member secured at one end to the lower end of the shaft and a tensioned leg pivotally connected to the said member adapted to depend below the bottom side of the fuselage.

In testimony whereof I affix my signature.
LESTER GUY QUERRY.
